AUTOMATIC SWITCH FOR STARTING-
MOTORS ON AUTOMOBILES

Louis Frank Jezek, Temple, Tex.

Application August 13, 1947, Serial No. 768,424

2 Claims. (Cl. 200—83)

1

My invention relates to improvement in electric switches and more particularly to switches used for the starting-motor of an automobile engine.

The principal object of the invention is to provide a switch so constructed that, after having been set to close an electric circuit for starting the motor, the switch will automatically open, after this function has been performed.

In order to start a car, provided with my switch, the ignition is first turned on and the gear lever put into neutral position. A flexible operating wire is then caused to run out far enough to engage and move a starter switch button to switch closing position and thus energize the starter. As soon as the engine is running, the reduced pressure in the air intake manifold will cause a reduced pressure in a diaphragm casing, which effects movement of the starter button away from the flexible rod to open the starter switch. If the engine should be stalled, this button moves out to a position where contact is again made with said rod and the starter switch is closed.

These and other objects and advantages will be made clear from the subjoined description with the aid of the attached drawings, wherein like numerals denote the same details in the different views.

One embodiment of the invention is illustrated in the accompanying drawing wherein

Figure 1 represents a side elevation of the automatic switch and the flexible operating rod with connections;

Figure 2 is a vertical section along an axial plane at right angles to Figure 1;

Figure 3 is an end view as seen from the manifold or suction end of Figure 1.

Figure 4 is a vertical section through the switch housing showing the button controlling spring and the bridging element.

In the drawing numeral 10 denotes a portion of the intake manifold of an automobile engine. To the suction pipe 11 for the manifold is attached a screw plug 12 which is part of a vacuum cell or diaphragm casing 13 between the two end cups 14 of which is stretched a diaphragm 15 in the usual manner. On one side of said diaphragm is secured the end of a sliding stem or bar 16 which is guided in a yoke 17 to which the casing 13 is bolted.

The end of the sliding stem or bar 16 has a foot 18 at right angles thereto on which is placed a small housing 19 containing a spring actuated switch push button 20. This button carries a

bridging element 20a adapted to make contact between the terminals 21 when pushed up.

To the end of an arm on the yoke 17 is clamped, as at 22, one end of the guide tube 23 of a Bowden wire through which is slidably extended the flexible wire 24, the working end 25 of which extends beyond the end of the tube 23, in alignment with the bush button 20.

The opposite end of the flexible guide tube 23 is clamped as at 26 to a bracket 27 which is hung on the dash board or on the steering wheel in convenient position for the driver to reach. The operating end of the flexible wire 24 extends beyond the end 26 of the guide tube 23 and is provided with a knob or handle 28. This knob 28 may be grasped by hand to shift the wire 25, or it may be placed in a position where, by laterally moving the gear shift lever when such lever is in neutral position, the lever may press against the knob to cause the desired shifting of the wire.

This switch for the starting motor operates as follows: In order to start an automobile provided with my automatic switch, the ignition circuit is first closed in the customary manner and the gear lever put in neutral. By then pushing the wire 24 by hand, or by lateral movement of the shift lever as described, the wire end 25 will be projected to press the button 20, thereby closing the starter circuit at 21. When the engine starts the reduced pressure produced in the manifold causes the diaphragm 15 to be lifted, thereby raising the housing 19 and permitting the spring to push the button 20 down and remove the bridging element 20a from electrical connection with the contacts 21. Suction now remains on the diaphragm until the motor stalls. Then the diaphragm 15 returns to its normal or central position, as seen in Figure 2, thereby dropping the stem 16, so that the button 20 is again pressed against the operating end 25 of the flexible rod 24, which has remained by friction in the position to which it was first moved, and automatically closes the circuit at 21.

It is to be understood that the invention as herein disclosed may be varied from the details described and shown without departure from the spirit of the subjoined claims.

I claim:

1. Automatic starting mechanism for an internal combustion engine having an intake manifold and an electric starting motor, comprising a vacuum cell, having a partitioning diaphragm a tubular connection between one side of said cell and the intake manifold whereby reduction of pressure in the manifold will effect the movement

of the diaphragm in one direction, a stem connected with the opposite side of the diaphragm from the tubular connection and extending outwardly from said cell, a circuit closing switch including a housing, a pair of terminals carried thereby, a spring pressed element in the housing and a bridging contact carried by said element which, upon movement of the element in one direction electrically connects said terminals, said switch being mounted upon and carried entirely by said stem, and a reciprocable switch closing member supported for movement toward and away from said spring pressed element and adapted when moved in one direction to engage the spring pressed element and move the same to switch closing position, the movement of the diaphragm under the effect of the vacuum in the manifold effecting the shifting of the entire switch unit and movement of the spring pressed element away from the reciprocable member permitting opening of the switch.

2. Automatic starting mechanism for an internal combustion engine having an intake manifold and an electric starting motor, comprising a vacuum cell having a diaphragm, a tubular connection between one side of said cell and said manifold whereby reduction of pressure in the manifold effects the movement of the diaphragm in one direction in the cell, a guide yoke attached to the cell, a stem connected with the diaphragm upon the side opposite from the tubular connection and extending outwardly through the guide yoke, a starting motor switch carried by the sliding stem and including a housing, terminals on the housing, a spring pressed button in the housing and means carried by the button for bridging the terminals, and means for effecting the closing of the switch comprising a recip-

rocably supported wire attached at one end to said yoke for movement in a line paralleling the movement of the sliding stem and in alignment with said switch button, and means facilitating the reciprocation of the wire from a position remote from the switch, said wire when moved in one direction having said end thereof pressed against the switch button to effect the closing of the switch, the movement of the diaphragm under the effect of vacuum created in the intake manifold moving the entire switch away from the said one end of the wire to permit the spring pressed button to move to switch opened position.

LOUIS FRANK JEZEK.
